UNITED STATES PATENT OFFICE.

ROBERT J. G. BLOCKOUSE, OF PHILADELPHIA, PENNSYLVANIA, ASSIGNOR TO ALCORN,
BLOCKOUSE & CO., OF PHILADELPHIA, PENNSYLVANIA, A FIRM CONSISTING OF
JAMES S. ALCORN AND ROBERT J. G. BLOCKOUSE.

HEATING-FURNACE.

1,335,648.

Specification of Letters Patent. Patented Mar. 30, 1920.

Application filed August 7, 1918. Serial No. 248,782.

To all whom it may concern:

Be it known that I, ROBERT J. G. BLOCKOUSE, a subject of the King of Belgium, residing in Philadelphia, Pennsylvania, have 5 invented certain Improvements in Heating-Furnaces, of which the following is a specification.

One object of my invention is to construct a furnace in which the article to be 10 treated can be intermittently traversed through the furnace and brought to a predetermined heat.

A further object of the invention is to provide a furnace in which the articles can be 15 brought to a predetermined heat through a varying heat in the furnace.

A still further object of the invention is to provide means for automatically charging the furnace with the articles and for dis- 20 charging the articles after they have been brought to the heat desired.

These objects I attain in the following manner, reference being had to the accompanying drawings, in which:

25 Figure 1 is a longitudinal sectional view on the line 1—1, Fig. 4;

Fig. 2 is a side view, partly in section, on the line 2—2, Fig. 4;

30 Fig. 3 is a view of the feed end of the furnace;

Fig. 4 is a transverse sectional view on the line 4—4, Fig. 1;

Fig. 5 is a detached perspective view illustrating one of the lifters;

35 Fig. 6 is a detached perspective view illustrating one of the supports;

Fig. 7 is a sectional perspective view illustrating one of the lifting beams and the lower sections of the lifters;

40 Fig. 8 is a longitudinal sectional view illustrating a modification of the invention, and Fig. 9 is a sectional view on the line 9—9, Fig. 8.

The base of the machine, in the present 45 instance, is made of longitudinal I-beams 1 and transverse I-beams 2 to which are attached upright beams 3 carrying the floor beams 4 of the furnace structure 5 which has a bottom plate 6, a brick lining 7 and 50 an arched roof section 8, also of brick. At each side of the furnace structure are burner openings 9. Burners are located in these openings and play, in the present instance, upon granular material in the fire chamber

10 at each side of the furnace so that the 55 flames pass over the articles within the furnace and heat them to the degree required. There are a number of these burners throughout the length of the furnace so that the temperature can be varied, as desired. 60 In the present instance, the furnace is a double furnace having a partition wall 11, but it will be understood that my invention can be used as a single furnace as well. At each end 12 of the furnace is an opening 13, one 65 for the entrance of the article to be heated and the other for the discharge of the same. In front of these openings is a chain door 14, consisting of a series of chains loosely hung from one or more transverse shafts, so 70 that when the article is fed into the furnace these chains separate and as the article passes the chains they assume a closed position. This arrangement tends to keep the major portion of the heat in the furnace. 75

Extending longitudinally of the furnace is a shaft 15 mounted in bearings 16 carried by the beams 2. Extending parallel with the shaft 15 are two I-beams 18, which are arranged to be raised and lowered by the cams 19 on the shaft 15 and levers 20 pivotally mounted in bearings 21 and 22. On the inner end of each lever is a roller 23 which bears against its particular cam 19, while the other end has a roller 24 which bears against 85 the under side of one of the I-beams 18 so that as the shaft 15 rotates the I-beams are raised and lowered. Secured to the I-beams are lifters 25, which are adapted to guides 26 in the bed plate 6 of the furnace and 90 these lifters, in the present instance, are made in two parts 27 and 28, the part 27 being secured to the I-beams 18, while the part 28, which is detachably secured to the part 27, has a head 29 at its upper end, beveled 95 as shown in Figs. 1 and 5. The guides 30 extend through the brick work 7 in the bottom of the furnace and mounted in these guides is a support 31 for the article being heated. This support is shaped as shown 100 in Fig. 6 and has a beveled portion 31^a at the forward end and a curved stop 32 at the rear end. The head 29 is adapted to work in the recesses 33 in two adjoining supports 31 and is arranged to lift the article over 105 the stop 32 and allow it to roll over the surface 31^a of the adjoining support until it comes in contact with the stop 32 of another

- support, so that as the beams 18 are raised and lowered by the cams the article is lifted and allowed to roll forward intermittently through the entire length of the furnace and 5 the speed at which this movement takes place depends upon the speed at which the shaft is driven. The shaft, in the present instance, is driven slowly by a transverse power driven shaft 34, on which is a worm 35 meshing with a worm wheel 36 on the shaft 15.
- In the present instance, the articles to be heated are shell casings, which are cylindrical in form so that they will readily roll from one stop to another. In order to feed 10 these shell casings, or like articles, into the furnace, I provide two vertically arranged sliding stops 37 and 38 adapted to guides 39 directly in advance of the feed doors of the furnace. These stops are operated by 15 cams 40, mounted on shafts 41, adapted to bearings 42 on the frame. These shafts are geared to the main shaft 15 by gears 43 and 44, as clearly shown in Fig. 3. The platform 45, leading into the furnace, is slightly inclined and the shell casings are placed by the 20 operator on this inclined platform and come in contact with the stop 37 and, as it is withdrawn by the action of the cams, the other stop 38 is elevated so that each casing passes 25 the first stop and rolls against the second stop, the second casing resting against the first stop as it is elevated, while the first casing on the depression of the stop 38, rolls past the chain doors into the furnace and 30 comes in contact with the stop 32 of the first support 31. Then, as these heads are raised and lowered the shell casings are 35 intermittently fed forward through the furnace.
- At the discharge end of the furnace is an inclined platform 46 over which the shell casings roll after leaving the last carrier and the end of this platform 46 is curved upward, as at 47, so as to form a stop for the 40 casings, and they can be moved by any suitable means from this platform. The platform, in the present instance, is hollow, as shown, and may be either air or water 45 cooled.
- The supports 31 are removable so that when they become worn they can be detached and other supports substituted for them and the upper sections 28, having the heads 29, may also be removed for a like cause and 50 renewed.
- In the present instance, in the double furnace shown the cams are so set that one set of cams is elevating one beam 18, while the other set of cams is in such position as to 55 allow the other beams to be lowered. This arrangement relieves the shaft from the strain of lifting all of the shells in the furnace at the same time. By adjusting the burners, the heat in the furnace can be regulated at will so as to bring the shell casings,
- or other articles, gradually to the proper heat, and as it may be necessary to bring certain articles to one heat and other articles to another heat, this heat can be readily accomplished by the arrangements above 60 described.
- In Figs. 7 and 8, I have illustrated a modification of the invention, in which there are two cam shafts 15^a driven through worm and worm gearing from a transverse shaft 75 35^a, which, in turn, is driven by worm and worm gearing from a shaft 48 and, in this instance, there is a cam 19^a for each lifter 25, which is made in substantially the same manner as the lifter shown in Figs. 2 and 4. 80 The means for feeding the shells to the furnace is substantially the same as that previously described, only the cams 40^a are mounted directly on the cam shafts 15^a.
- The operation of the furnace is as follows: 85
- Referring to Figs. 1 to 4 inclusive, the furnace is heated to the desired degree, one portion of the furnace being brought to a greater heat than another portion. The shell casings to be heated are mounted on the 90 platform 45 and the mechanism is set in motion and the casings are automatically fed, one at a time, into the furnace past the inlet chain doors by means of the reciprocating stops 37 and 38, and they are intermittently 95 fed forward on the reciprocation of the carriers 25, which elevate the casings so that they will be free of the stops 32 and will roll over the surface 31^a of the support to the next stop, and so on, intermittently, throughout 100 the length of the furnace. The shells pass the chain door at the discharge end of the furnace and onto the platform 46.
- I claim:
1. The combination in a heating furnace, 105 of a furnace structure, a series of supports therein having stops; and a reciprocating carrier arranged to elevate the articles being heated above the stops of the supports, allowing the articles to roll over the surface of the supports and against the next stop so that the articles being heated are moved intermittently through the furnace.
  2. The combination of a heating furnace; 110 a series of supports therein mounted in a fixed position and arranged one in advance of the other throughout the length of the furnace, each of said supports having an inclined surface and a stop; a reciprocating lifter arranged at each stop; means for raising the lifter so as to elevate the article and to allow it to roll over the stop of one support and against the stop of another support; and means for feeding articles, one at 115 a time, into the furnace, actuated in time with the means for feeding articles through the furnace.
  3. The combination in a heating furnace 120 for shells and like cylindrical objects, of a furnace structure; a series of supports ar- 125

ranged in advance of the other throughout the length of the furnace, each support having a beveled face and a stop; a series of lifters having heads beveled in the same direction as the bevel of the supports and arranged to elevate the shells above the stops, allowing them to roll over the inclined surface of a support to the next stop.

4. The combination in a heating furnace for shells and like articles, of a furnace structure; two series of supports arranged throughout the length of the furnace, one series paralleling the other series; a series of lifters for each series of supports, said lifters having their upper surface beveled in the same direction as the bevel of the supports; and a central cam shaft having cams thereon for actuating the lifters of both series.

5. The combination in a heating furnace, of a heating chamber; two sets of supports therein, each support having an inclined surface and a stop; two longitudinal beams; lifters mounted on the beams and having heads shaped to lift the shell casings, and like articles, above the stops, allowing each article to roll over the inclined surface of the next stop; a shaft parallel with the beams; cams on the shaft; and levers actuated by the cams and arranged to lift the beams and their lifters.

6. The combination in a heating furnace, of a furnace structure having a series of re-

movable supports therein arranged throughout the length of the furnace, said supports having an inclined surface and a stop; lifters at each support; means for raising the lifters so as to lift each article over a stop, allowing it to roll over the support to the next stop; two reciprocating stops at the feed end of the furnace, one arranged in advance of the other; a shaft; cams on the shaft for actuating the stops so that when one is raised the other is lowered in order to feed the shell casings, or like articles, into the furnace, one at a time.

7. The combination in a heating furnace, of a bottom plate; a series of guides located in the bottom plate; a lining for the interior of the furnace; a series of supports mounted on the upper ends of the guides, said supports being detachable so that they can be renewed, the upper surface of each support being beveled at one end and having a curved stop at the other end; lifters adapted to the guides and having heads with beveled upper surfaces arranged to lift the articles being heated above the stops so that they will roll over the inclined surface of the supports, said lifters being made in two parts secured together; a longitudinal beam to which the lower part is secured; a cam shaft; and cams for elevating the beam and the lifters carried thereby.

In witness whereof I affix my signature. 65
ROBERT J. G. BLOCKOUSE.
